UNITED STATES PATENT OFFICE.

WILLIAM LUNHAM, OF BRONXVILLE, AND WALTER MOORE, OF NEW YORK, N. Y.

PORTABLE HEATER.

1,105,983.

Specification of Letters Patent.

Patented Aug. 4, 1914.

Application filed May 11, 1914. Serial No. 837,722.

To all whom it may concern:

Be it known that we, WILLIAM LUNHAM, residing at Bronxville, Westchester county, State of New York, and WALTER MOORE, of New York city, county and State of New York, citizens of the United States, have invented an Improvement in Portable Heaters, of which the following is a specification.

Our invention relates to portable heaters designed for use with solidified liquid fuel, such as shown in the Perelzveich and Rosenbusch Patent Number 922,503 of May 25, 1909; and it comprises certain improvements on the type of device therein illustrated, having for their general objects to render the heater more convenient and satisfactory in use, and at the same time to secure a very simple and cheap construction.

In the accompanying drawings illustrating the invention: Figure 1 is a side elevation of the improved device with the vessel supports collapsed against the holder; Fig. 2 is a vertical section showing the can burner somewhat elevated; Fig. 3 is a horizontal section; and Fig. 4 is a detail of a portion of the holder spread out flat at the region of a sleeve.

In accordance with the present invention a can burner 1, designed to hold solidified alcohol, is mounted for vertical, frictional adjustment, to bring the flame nearer to or farther from the vessel being heated, within a tubular holder 2, to which the vessel-supporting frames 3 are hinged for horizontal adjustment. The holder is open at both ends, and expandable, while the can burner is of such diameter as to fit forcibly into the holder, being capable of being pushed up or down and held at any degree of vertical adjustment, within limits, relatively to the frames 3 and the vessel that may be supported thereby. The said frames or wings 3 are of the general character disclosed in the prior patent aforesaid, each having legs 4 and 5 and a connecting horizontal top member 6, the legs 4 being pivotally received in sleeves 7, and the top members constituting a supporting base which is expandable or contractible according to the size of the vessel to be heated. Thus the frames can be collapsed against and surrounding the holder, as shown in Fig. 1, in condition for carrying, or they may be swung outward as shown in Fig. 3, or to any position desired.

The holder 2 is made of a strip of sheet metal which is curved into tubular form and

its ends united by a vertical seam 8 of suitable formation. At intervals the material of the holder wall is bent or looped outward so as to form the vertical sleeves 7, these sleeves being continuous with the wall portions at both sides of them and affording in effect vertical slits or slots 9 in the internal wall, which give slightly when the can burner 1 is forced into the holder and enable the latter to clasp the burner reliably at any height. These openings extend all the way to the edges of the holder, but the sleeves preferably terminate at a short distance therefrom, the marginal portions being bent or rolled over to form reinforcements 10.

As indicated in Fig. 4, the strip of metal of which the holder is formed has material cut away at intervals in the marginal regions which are to be rolled over to form the reinforcing beads 10, and it is the body portions 12 in vertical alinement with these notches 11 which are curved outward to form the sleeves 7. The making of these sleeves brings the edges of the recesses 11 together or substantially together, so as to form in effect continuations of the sleeve slits. In a similar manner the marginal regions are cut away at the ends of the seam 8.

The can burner 1 is capable of manufacture in a simple manner and at very low cost, and is preferably provided with an ordinary form of slip closure 14.

In accordance with our improved construction, the adjustment of the burner toward and from the receptacle resting on the supports 3 is not secured by sliding the part bearing the sleeves 7 on the legs 4, but, as explained, by pushing the burner up or down in its clasping holder. In fact any substantial extent of vertical movement of the holder is preferably prevented by offsets 15 in the legs 4 immediately above the upper ends of the sleeves, though preferably a slight amount of movement is permitted so that the holder can either rest on an underlying surface, as shown in Fig. 2, or slightly raised above it, as in Fig. 1. The former arrangement is somewhat more stable, but in event of danger of heat transmitted downward through the holder injuring the surface beneath, the holder may be caused to clear the same.

In order further to guard against the bottom of the holder becoming sufficiently heated to injure a table or the like on which it

may be placed, and also to guard against the overheating of a confined body of air below the can burner, so as to melt the solidified fuel therein, the holder is provided adjacent its lower end with a series of ventilating openings 16 extending all the way around the same.

In Fig. 2 the fuel in the can burner is shown almost exhausted, but initially it will be understood the can is full, and preferably when the charge is completely exhausted the can is discarded and another, filled can procured to take its place.

The offsets 15 in the pivotal legs of the vessel supports are so formed and positioned as to overlie the upper edge of the can burner when the supports are closed against the holder in condition for carrying, as shown in Fig. 1, thus preventing dislodgment of the burner from the holder under such conditions. In Fig. 3, which represents the supporting frames as swung outward from the holder, one of them is also shown by dotted lines as folded against the holder, so that its offset portion occupies the position described.

What we claim as new is:

1. A portable heater, comprising an expandable holder, and vessel supporting frames each comprising legs and a connecting top member hinged by one leg of each at spaced points to the sides of the holder, whereby the frames may fold into compact relation with the holder or be adjusted outward therefrom, in combination with a can burner designed to hold solidified liquid fuel, said burner being of such diameter as to fit forcibly into said expandable holder and to be held at various degrees of vertical adjustment therein.

2. A portable heater, comprising a tubular holder having a distributed series of vertical expansion regions comprising portions of the holder wall bent outward to form external sleeves continuous with the wall portions at opposite sides and affording vertical splits in the internal wall extending from top to bottom of the holder, a can burner designed to contain solidified liquid fuel vertically and frictionally adjustable in said holder, and vessel-supporting frames having one leg of each rotatably received in said sleeves.

3. A portable heater, comprising a tubular

holder formed of a strip of sheet metal having sections cut out of its marginal portions at intervals and said marginal portions bent over to form reinforcements, the body portions of the wall of the holder vertically in line with the cut out sections of the said marginal portions being bent outward to form external vertical sleeves, in combination with a can burner designed to contain solidified liquid fuel within said holder, and vessel-supporting frames having one leg of each 65 rotatably received in said sleeves.

4. A portable heater, comprising a tubular expandable holder having ventilating openings in its lower portion, a plurality of vessel-supporting frames each comprising 70 legs and a connecting top member hinged by one leg of each at spaced points to the body, and a can burner designed to contain solidified liquid fuel vertically and frictionally adjustable in said holder.

5. In a portable heater, the combination of a tubular holder, a removable can burner designed to hold solidified liquid fuel vertically and frictionally adjustable in said holder, and collapsible and adjustable vessel-supporting means comprising frames 80 each having legs and a connecting top member hinged by one leg of each at spaced points to the body.

6. In a portable heater, the combination 85 of a holder, a removable can burner designed to hold solidified liquid fuel in said holder, and collapsible and adjustable vessel-supporting means comprising frames each having legs and a connecting top member 90 hinged by one leg of each at spaced points to the body, the pivotal leg of one or more of said frames having an offset portion adapted when the frame is folded against the holder to overlie the upper edge of said burner.

7. A portable heater, comprising a holder having a distributed series of external vertical sleeves, a can burner designed to contain solidified liquid fuel vertically and frictionally adjustable in said holder, and vessel-supporting frames having one leg of each 100 rotatably received in said sleeves, the said legs having offset portions above said sleeves.
